UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

METHOD OF MAKING CARBOLIC ACID.

1,274,394.

Specification of Letters Patent.

Patented Aug. 6, 1918.

No Drawing.

Application filed July 10, 1916. Serial No. 108,293.

To all whom it may concern:

Be it known that I, HERBERT H. Dow, a citizen of the United States, and a resident of Midland, county of Midland, and State of Michigan, have invented a new and useful Improvement in Methods of Making Carbolic Acid, of which the following is a specification, the principle of the invention being herein explained and the best mode in 10 which I have contemplated applying that principle, so as to distinguish it from other inventions.

The present improved process relates more particularly to the synthetic production of carbolic acid, or phenol, in contradistinction to its recovery from the co-called carbolic oil fraction of coal tar.

It has been generally accepted heretofore that the phenols cannot be prepared from 20 the halogen derivatives of benzol, *i. e.* from chloro-, bromo-, or iodo-benzene, in the same way as the alcohols from alkyl chlorids, bromids or iodids, the halogen being bound too firmly to the benzene nucleus. On the 25 other hand, if nitro-groups are present in proper position, an exchange of this kind can be effected by heating with aqueous sodium or potassium hydroxids, and the same is true of benzene-sulfonic acid, the 30 resulting alkaline phenate in either case being readily converted into phenol by any acid, even by a very weak acid, like carbon dioxid in water.

I have found, however, that mono-brom- 35 benzol (C_6H_5Br), contrary to the accepted view, based on experience with mono-chlor-benzol, will react with dilute caustic soda under conditions of temperature and pressure easily attainable in commercial practice. Such reaction results not only in the 40 production of the sodium phenate desired for use in order to convert the same into phenol, but the bromin present in the benzene compound is recovered in the form of 45 sodium bromid, which is a valuable commercial product, so that there is no loss of bromin, except, of course, the small amount that inevitably disappears in all chemical reactions carried out on a commercial scale.

50 The present invention accordingly consists of the steps and means hereinafter fully described and particularly pointed out in the claims, the specific improvement disclosed

constituting but one of various ways in which the principle of the invention may 55 be used.

As already indicated in the present process I utilize mono-brom-benzol by treating the same with dilute caustic soda under a temperature that will produce approximately 60 300 pounds pressure. Under such conditions of temperature and pressure, the following reaction will proceed in a satisfactory manner, *viz.*:

The resulting sodium phenate is then converted into carbolic acid, or phenol, in the fashion already familiar to chemists as 70 stated above, *viz.*, by treating the same with any suitable acid, even a weak acid such as that formed by a solution of carbon dioxid effecting the desired transformation, as illustrated by the following reaction, *viz.*:

The sodium bromid resulting from the first reaction given above is a valuable product in itself, and so no additional expense, 80 but rather the contrary, is involved in using the bromin substitution product of benzol. Furthermore, the operative conditions with respect to temperature and pressure are readily maintainable and the process described has hence proved a very satisfactory one for the synthetic production of carbolic acid, which on account of its purity is not only excellently suited for pharmaceutical purposes, but has to be used in various industries *e. g.* in the manufacture of picric and salicylic acids, since the cresols found as impurities in tar phenol are very undesirable in such industrial use and are 85 practically impossible to eliminate entirely.

90 Other modes of applying the principle of my invention may be employed instead of the one explained, change being made as regards the method herein disclosed, provided 95 the step or steps stated by any of the following claims or the equivalent of such stated step or steps be employed.

I therefore particularly point out and claim as my invention:

1. In a method of making phenol synthetically, the steps which consist in treating a

bromo-derivative of benzene with an alkaline hydroxid solution, whereby the phenate of such alkali is produced; and then adding an acid to such phenate, whereby the latter is converted into phenol.

2. In a method of making phenol synthetically, the steps which consist in treating mono-brom-benzol with an alkaline hydroxid solution, whereby the phenate and bromid of such alkali are produced; and then adding an acid to such phenate, whereby the latter is converted into phenol.

3. In a method of making phenol synthetically, the steps which consist in treating mono-brom-benzol with a dilute solution of sodium hydroxid, whereby sodium phenate and sodium bromid are produced; and then

adding an acid to such phenate, whereby the latter is converted into phenol.

4. In a method of making phenol synthetically, the steps which consist in heating a mixture of mono-brom-benzol and a dilute solution of sodium hydroxid to a temperature producing a pressure of approximately 300 pounds, whereby sodium phenate and bromid are produced; and then adding an acid to such phenate, whereby the latter is converted into phenol.

Signed by me, this 7th day of July, 1916.

HERBERT H. DOW.
